DESIGN FOR A BOOTEE

Kate R. Strauss, New York, N. Y., assignor to Famous Bathrobe Co., Inc., New York, N. Y., a corporation of New York

Application May 5, 1947, Serial No. 138,820

Term of patent 14 years

(Cl. D7—7)

To all whom it may concern:

Be it known that I, Kate R. Strauss, a British Stateless person, have declared my intentions of becoming a citizen of the U. S., residing at Manhattan, in the county of New York and State of New York, have invented a new, original, and ornamental Design for a Bootee, of which the following is a specification, reference being had to the accompanying drawing, forming part thereof.

In the drawing

Fig. 1 is a side view of a bootee, showing my new design;

Figs. 2 and 3 are top and bottom views thereof, and

Fig. 4 is a top view of the bootee as it appears after the ties have been opened and the bootee folded flat with the back thereof resting on the upper and sole.

I claim:

The ornamental design for a bootee, as shown.

KATE R. STRAUSS.
